LUMINESCENT TUBE ELECTRODE
RECEPTACLE

Charles M. H. Nelson, Los Angeles, Calif.

Application June 20, 1932. Serial No. 618,223

17 Claims. (Cl. 173—328)

This invention has to do in a general way with cover receptacles designed to enclose electrodes of inert gas tubes of the type used in electric signs and the like, and is more particularly related to improvements in electrode receptacles of the type shown and described in my copending application, Serial No. 521,684, filed March 11, 1931.

It is the general practice in the construction of signs of the general type referred to above, to mount the gas tubes on the outside of the sign body or case and have the electrodes project within the enclosure. The electrode receptacles are generally mounted on the inside surface of the sign face and project transversely across the case. This affords protection against mechanical injury to the tube; reduces the possibility of accidental contact of uninsulated high voltage parts by persons having access to the interior of the sign; and provides means for supporting the high tension conductors and connecting them to the tube electrodes.

This invention relates to the so-called pendant type of electrode receptacle which is mounted in the general manner referred to above and includes certain improvements in this type of receptacle which facilitates its construction and installation, and affords further protection against short circuits and corona effects. In the usual type of electrode receptacle of this type, so far as I am aware, the conducting cable enters the pendant end of the electrode in substantially normal relation thereto so that a portion, at least, of the conductor cable is in close proximity of the rear wall of the sign case, unless the case is made especially large to avoid this situation.

It is a primary object of this invention to produce an electrode receptacle of the class described which is so constructed that the conductor cable enters the electrode receptacle at an angle or in an inclined position. This construction has the effect of maintaining the conductor cable in substantially the center of the sign case. In accomplishing this object, I construct the electrode receptacle so that the entering end of the conductor cable is sheathed with an overlying material portion. In this manner any possible exposure of the conductor which extends beyond the insulation of the cable is avoided.

It is a further feature of the invention that the sheath is constructed so that the cable is not bent sharply but has a curve of long radius so that the thickness of the cable insulation at the point at which it enters the receptacle is not reduced at

any point as would be the case if the cable were bent at a sharp angle.

It is a further object of this invention to provide a receptacle of the class described with a breathing opening so that there will be no pronounced tendency to retain moisture within the electrode receptacle.

The general construction of the device whereby the foregoing objects are accomplished comprises a housing which has an elongated tube receiving socket in one end, such socket terminating in what I may term a transverse wall above or beyond which I provide a transverse chamber. The peripheral or side wall of the housing at one portion thereof is provided with an inclined channel or passage associated with a sheath which communicates with the transverse chamber and through which a conductor cable is admitted to the chamber for contact with a suitable conductor which delivers energy to the tube received in the socket.

It is a further object of this invention to taper the socket referred to above and to form the outer surface of the housing on an inclined or offset taper so that one portion of the housing wall increases in thickness from the basal supporting flange to the pendant or inner end. In this manner I provide sufficient material in the wall of the housing to permit the formation of a channel or passage therein without destroying the dielectric effect of the housing wall.

The details in the construction of the certain preferred forms of my invention, together with other objects attending its production, will be best understood from the following description of the accompanying drawings which are chosen for illustrative purposes only, and in which—

Fig. I is a perspective view with parts broken away illustrating a preferred form of electrode receptacle embodying a form of my invention, and showing the manner in which it is mounted in a sign case;

Fig. II is a sectional view taken in a plane represented by the line II—II in Fig. I;

Fig. III is a perspective view illustrating a cover section of the type used in connection with the receptacle shown in Fig. I;

Fig. IV is a detached view showing a preferred form of cable mounting used in the device shown in Fig. I;

Fig. V is a sectional elevation illustrating another form of electrode receptacle.

Fig. VI is a sectional view taken in a plane represented by the line VI—VI in Fig. V;

Fig. VII is an end view of the receptacle shown

105

110

- in Fig. V, the same being illustrated with the cover section removed; 80
- Fig. VIII is an elevational view of the cover section used in the receptacle shown in Fig. V; 85
- 5 Fig. IX is a plan view taken in the direction of the arrow IX in Fig. VIII;
- Fig. X is an end view of a preferred form of conductor bracket used in the receptacle shown in Fig. V;
- 10 Fig. XI is a sectional elevation showing another modified form of my invention;
- Fig. XII is a sectional view taken in a plane represented by the line XII—XII in Fig. XI; 90
- 15 Fig. XIII is an end view taken in the direction of the arrow XIII in Fig. XI;
- Fig. XIV is a plan view of a preferred form of a conductor connection used in a receptacle shown in Fig. XI; and 95
- 20 Fig. XV is an elevational view illustrating the construction of a cob section used in the receptacle shown in Fig. XI.
- Referring to the drawings with particular reference to Figs. I, V and XI, reference letter A indicates an electrode receptacle, made preferably of non-absorptive vitreous material such as wet process high potential porcelain with a hard glaze coat, which is mounted on the front face B of a sign case C, the sign case being composed of a rear face D and top or boundary faces E. The receptacle A is provided with a basal flange F adapted to engage the inner surface of the front face B and is supported thereon by means of oppositely disposed ears G which receive screws indicated by reference letter H. Reference letter I indicates a rarified gas tube or sign tube of the so-called neon type, the inner end J of such tube being provided with a suitable electrode, and means generally indicated by reference letter K in Figs. I and V and reference letter K' in Fig. XI are provided for delivering electric current to the electrode. Reference letter L indicates an insulated cable having a conductor M through which current is delivered to the sign electrode from any source of high potential energy not shown. Means are provided in the receptacle for electrically connecting the cable to the conductor member K or K'. The details in the construction of such means will be more completely described later in the specification. 100
- 30 It is an important feature of all the different forms of my invention that the means for admitting the cable to the electrode receptacle are constructed so that the entering end of the cable is completely insulated and enters the receptacle at a substantial distance from the rear face D. The cable is supported at various intervals throughout its length by suitable insulating supports of any desired type, such as indicated by reference letter N in Fig. I or reference letter O in Fig. V. These supports are secured to the rear plate D in any suitable manner such as by means of screws or bolts. The sign tube I is also supported at various points by means of suitable supporting clamps generally indicated by reference letter P, which are secured to the front face plate B by means of metal screws Q. 110
- 35 More particularly describing the various modifications of my invention with especial reference to Fig. I, the electrode receptacle is shown as comprising, what I may term, a basal section 11 which has a deep tapered socket 12, the socket terminating in, what I may term, a transverse wall 13. The transverse wall 13 is apertured as indicated at 14 for the reception of a conductor bolt 15. The bolt 15 engages a washer 16 on the inside of the socket 12 and the outer threaded end of the bolt engages a nut member 17, the details in the construction of which are best illustrated in Fig. IV where it is shown as comprising a base section 18 having an internally threaded thimble 19 over which a washer 20 is adapted to fit. In the use of this device the conductor cable M is wound around the thimble portion 19 as indicated at 21 and the elements are drawn into pressure engagement by tightening the screw 15 in the thimble with the washer 20 bearing against the outer surface of the transverse wall 13. 105
- 40 Reference numeral 22 indicates a cover section which is provided with a peripheral recess 23 adapted to fit over an outwardly extending shoulder on the basal section 11 and which is undercut as indicated at 24 so as to form, what I may term, a transverse chamber 25 in the housing beyond the deep socket 12. In constructing the basal section of the housing or receptacle shown in Fig. I, I propose to provide this section with an offset taper so that the peripheral wall thickness, of what would be the lower side, increases from the basal portion at the end portion, such wall 110 section being indicated generally by the arrow S—S. This is accomplished preferably by making one portion of the outer wall substantially parallel with the axis of the receptacle and tapering the remaining of the surface toward this straight portion. In the upper end portion of the outer wall surface in the thick section thus formed, I provide an inclined channel indicated by reference letter V, and in this particular form of my invention, the inclined channel is associated with a sheath or shield 28 which is composed of insulating material which is integral with the basal section of the housing. The shield and the channel cooperate to form an inclined passage for the reception of the contact end of the cable L. The inclination and the arrangement of this passage is such that the cable L enters the passage at a point substantially midway between the face plates B and D of the sign case. The sheath provides adequate protection 120 against corona or arcing-over effects from the cable to the rear plate, and the angle of inclination is such that the cable does not receive a sharp bend or kink as it enters the receptacle from the support N, it being understood that such kinks tend to decrease the thickness of insulation in the region where the kink occurs. 125
- 45 The cover member 22, in this form of my invention, is secured to the basal section in any suitable manner such as by means of paste porcelain so that the unit when assembled forms what is in effect an integral housing. 130
- 50 In this form of my invention, the conducting member K is made in the form of a coil spring 30, one end of which bears against the head of the screw 15 and the other end of which bears against a metal conducting thimble 31 which is mounted in a glass thimble 32, such thimble being connected with the electrode end of the tube I by means of a glass hub 33. Current is 135 delivered from the thimble 31 to the electrode 34 by means of a wire or other conductor 35 embedded in the hub 33. 140
- 55 In the form of my invention shown in Figs. V to VIII inclusive, the receptacle A comprises a basal section 40 which is shown as being provided with a deep socket 41 which extends longitudinally therewith, the socket having a rubber or other composition plug 42 in its open end adapted to receive and support the sign tube I. The inner or 145
- 60
- 65
- 70
- 75

pendant end of the socket terminates in a transverse wall 43 which is provided with an aperture 44 adapted to receive a conductor screw or bolt 45.

The socket in the basal section of the housing 5 in this form of my invention, like that described above, is tapered and the outer surface of the basal section is formed with an "offset taper" so that one portion of the wall indicated at S'-S' 10 is of increased thickness from the base to the pendant end. This portion of the basal section is provided with a channel or recess indicated at 46 and the portion of the basal section opposite the channel 46 is extended as indicated at 47 to form an interlocking support for a cover member 48. The engaging portions of the cover member 15 and the basal section are stepped as indicated at 48' and the cover member is held in tight engagement with the basal section by means of a stud 49 which extends through an opening in the extending portion 47 of the basal section into threaded engagement with the cover section. The inner portion of the cover member 48 is recessed as indicated at 50 and the cover member 20 is made of a length such that the unit when assembled has a transverse chamber 50' between the partition 48 and the cover section.

Reference numeral 51 indicates an angular conductor which is mounted on the screw or bolt 45 and has an upwardly extending leg perforated 25 to receive a bolt 52 whereby the conductor end of the cable L may be secured thereto. In this form of my invention the cover member is provided with a downwardly extending and inclined sheath or lip 53 which cooperates with the channel or recess 46 to form an inclined passage for the reception of the insulated cable. This lip is shown as being knurled as indicated at 54 for the purpose of clamping the cable in place and relieving the binding post or conductor of strain 30 from the cable. The sign tube electrode and conducting system is the same in this form of my invention as that shown and described in connection with Fig. I, the spring 30 contacting with the head of the bolt 45.

45 In assembling this type of receptacle, the bolt and angle conductor or binding post 51 are first put in place and tightened, the cable being secured to the angle plate either before or after the placement thereof, and the cover member 48 is then put in place and secured to its position by means of the stud 49. It is preferable in assembling this unit to place a cementing compound on the stepped interlocking edges 48', and after such cement has set, the stud 49 is removed and the transverse chamber 50' is completely filled 50 with cement through stud passage. If desired, of course, the stud may remain a part of the assembly, but under these circumstances it is preferable to form the cover so that the stud is completely encased by insulating material.

55 In the form of my invention shown in Figs. XI to XV inclusive, I provide what may be termed a three-piece receptacle in which the receptacle A is composed of a basal section 60, a cob 61, and a cover section 62. The basal section 60 has a deep socket 63 extending longitudinally therein and the upper end of the socket is defined by an inwardly extending flange 64 which engages a shoulder 65 on the cob 61 so that the cob forms what is in effect a partition or transverse wall 60 at the inner end of the socket. The cob 61 is recessed as indicated at 66 to provide a transverse diameter and permit the installation of a screw or bolt 68 which supports a conductor plate 67 on the inner surface of the cob. In addition to

the conductor plate 67, the bolt supports a socket 68 adapted to receive a contact nipple 69 on the electrode end of the sign tube L. The plate 67 is provided with a finger 69 which normally extends in substantially the same plane or a plane substantially parallel to the plane of the plate 67 as shown in Fig. XIV.

In assembling this device the plate 67 and socket 68 is first secured for free adjustment on the cob 61 and the finger 69 bent down clear of the periphery of the shoulder on the cob and this assembly inserted from the plate attaching end, as shown in Fig. XI. The cable is then secured to the finger 69 by means of a bolt 70 and the cob and its associated parts are arranged so that the cable lies in an inclined recess 71 which is provided in the thick wall section t-t formed on the receptacle in the manner described in connection with Figs. I and V. The cover section 62 is then positioned as shown in Fig. XI where it is secured in place by means of a stud 73 which extends through a passage 74 in the cover section and into a threaded recess 75 in the cob or transverse wall section.

The cover 62, like the cover 46, is provided with 100 a sheath or lip 75 which extends downwardly over the recess 71 and protects or insulates, and guides the cable. This sheath is provided with knurling 77 like the sheath shown in Fig. V.

In all of the modified forms of the receptacle 105 referred to herein, I provide the basal section with a groove or channel indicated by reference letter V which is preferably an extension or depression in the cable receiving groove and is provided for the purpose of ventilating the interior 110 of the receptacle so as to prevent the accumulation of moisture therein.

It will be apparent from the foregoing description that the receptacle is, in all of its forms, of simple form and construction; it is convenient to 115 assemble; and when assembled, provides the maximum safety in sign units or other electric units which employ high tension electric current.

It is to be understood that, while I have herein described and illustrated certain preferred forms 120 of my invention, the invention is not limited to the precise construction described above, but includes within its scope whatever changes fairly come within the spirit of the appended claims.

I claim as my invention:

1. A light tube receptacle of the class described embodying: a housing composed of insulating material and having a deep socket extending longitudinally therein; an apertured transverse wall in said housing at the inner end of said socket; 130 and a transverse chamber formed in said housing above said transverse wall, the wall of said housing being provided with an inclined channel leading from an intermediate portion thereof to said transverse chamber and adapted to receive a 135 conductor cable.

2. A light tube receptacle of the class described embodying: a housing composed of insulating material and having a deep socket extending longitudinally therein; an apertured transverse wall 140 in said housing at the inner end of said socket; a transverse chamber formed in said housing above said transverse wall, the peripheral wall of said housing being provided with an inclined channel leading from an intermediate portion 145 thereof to said transverse chamber; and an inclined sheath on said housing extending over said channel so as to form an inclined passage for the reception of a conductor cable.

3. A light tube receptacle of the class described 150

- embodying: an integral housing composed of insulating material and having a deep socket extending longitudinally therein; an apertured transverse wall in said housing at the inner end 5 of said socket; and a transverse chamber formed in said housing above said transverse wall therein, the peripheral wall of said housing being provided with an inclined passage leading to said transverse chamber and adapted to receive a 10 conductor cable, said inclined passage having an external opening situated at a substantial distance below said transverse chamber.
4. For use in combination with a case adapted to support a light tube sign of the class described, 15 an electrode receptacle embodying: a housing having a deep socket extending longitudinally therein; means at the open bottom end of said housing for securing same to one wall of said case; an apertured transverse wall in said housing 20 at the inner end of said socket; and a transverse chamber formed in said housing above said transverse wall, the peripheral wall of said housing being provided with an inclined passage having an exterior opening situated substantially 25 midway between the walls of said case and an interior opening communicating with said transverse chamber.
5. For use in combination with a case adapted to support a light tube sign of the class described, 30 an electrode receptacle embodying: a housing having a deep socket extending longitudinally therein; means at the open bottom end of said housing for securing same to one wall of said case; an apertured transverse wall in said housing 35 at the inner end of said socket; a transverse chamber formed in said housing above said transverse wall, the peripheral wall of said housing being provided with an inclined channel terminating in said transverse chamber; and an 40 inclined sheath over said channel forming a passage adapted to receive a conductor cable.
6. For use in combination with a case adapted to support a light tube sign of the class described, 45 an electrode receptacle embodying: a housing having a deep socket extending longitudinally therein; means at the open bottom end of said housing for securing same to one wall of said case; an apertured transverse wall in said housing 50 at the inner end of said socket forming a transverse chamber in said housing, the peripheral wall of said housing being provided with an inclined channel terminating in said transverse chamber; and an inclined sheath over said channel forming a passage adapted to receive 55 a conductor cable, said passage having an exterior opening situated substantially midway between the walls of said case.
7. A light tube receptacle of the class described embodying: a housing composed of insulating material and having a deep socket extending longitudinally therein; an apertured transverse wall in said housing at the inner end of said socket forming a transverse chamber therein, the peripheral wall of said housing being provided 60 with an inclined channel leading to said transverse chamber; and an inclined sheath on said housing extending over said channel so as to form an inclined passage for the reception of a conductor cable, said sheath having a knurled 65 inner surface.
8. A light tube receptacle of the class described embodying: an integral housing composed of insulating material; a basal flange on said housing adapted to engage a supporting plate, said 70 housing being provided with a deep tapered 75
- socket extending longitudinally therein with its axis normal to said basal flange, and said housing being exteriorly provided with an offset taper so that one portion of the housing wall is of increasing thickness from the basal flange to the inner end thereof; an apertured transverse wall in said housing at the inner end of said socket, said housing having a transverse chamber formed in said housing above said transverse wall; an inclined channel formed in the portion of said wall which is of increasing thickness, said channel communicating with said transverse chamber; and a sheath formed over said channel so as to provide an inclined passage for a conductor cable. 80
9. A light tube receptacle of the class described embodying: a housing composed of insulating material and comprising an elongated basal section and a cover section, said basal section having a deep socket formed longitudinally therein; a transverse apertured end wall at the inner end of said socket, said cover section being recessed so as to form a transverse chamber above said end wall; and a downwardly inclined passage formed in the peripheral wall of said housing 90 and communicating with said transverse chamber for receiving the end of a conductor cable. 95
10. A light tube receptacle of the class described embodying: a housing composed of insulating material and comprising an elongated basal section and a cover section, said basal section having a deep socket formed longitudinally therein; a transverse apertured end wall at the inner end of said socket, said cover section being recessed so as to form a transverse chamber above 100 said end wall; a downwardly inclined passage formed in the peripheral wall of said housing and communicating with said transverse chamber for receiving the end of a conductor cable; and conductor means extending through the passage in 110 said end wall and adapted to secure said conductor cable in said transverse chamber. 115
11. A light tube receptacle of the class described embodying: a basal section having a deep socket extending longitudinally therein and terminating in an apertured end wall; an extending segment formed on said basal section and projecting beyond said end wall; a cover section engaging said extending segment and cooperating with said end wall and said segment to form a 120 transverse chamber above said end wall; means for securing said cover section to said basal section, said basal section being provided with an inclined channel terminating in said transverse chamber; and a sheath member formed on said 125 cover section and extending over said channel. 130
12. A light tube receptacle of the class described embodying: a basal section having a deep socket extending longitudinally therein and terminating in an apertured transverse wall; an extending segment formed on said basal section and projecting beyond said transverse wall; a cover section engaging said extending segment and cooperating therewith to form a transverse chamber above said transverse wall; means for securing said cover section to said basal section, said basal section being provided with an inclined channel terminating in said transverse chamber; a sheath member formed on said cover section 135 and extending over said channel; a conductor bolt extending through the aperture in said transverse wall; a conductor bracket secured to said bolt within said transverse chamber; and means for securing a conductor cable to said bracket. 140
13. A light tube receptacle of the class de- 145

- scribed embodying: a basal section having a deep socket extending longitudinally therein and terminating in an apertured transverse wall; an extending segment formed on said basal section 5 and projecting beyond said transverse wall; a cover section engaging said extending segment and cooperating therewith to form a transverse chamber above said transverse wall; means including a stud extending through an opening in 10 said extending segment into threaded engagement with said cover section for securing said cover section to said basal section, said basal section being provided with an inclined channel terminating in said transverse chamber; and a 15 sheath member formed on said cover section and extending over said channel.
14. A light tube receptacle of the class described embodying: a basal sleeve section having an inwardly extending flange formed on its inner 20 end; a cob in said sleeve section having a shoulder engaging said flange; a cover section mounted on said sleeve over said cob; means mounted in said cover and engaging said cob for locking all of 25 said sections in rigid engagement; conductor means mounted on said cob, said sleeve being provided with an inclined channel at its inner end; and a sheath on said cover section extending over said channel in spaced relation therewith and terminating in an opening opposite said 30 conductor means.
15. A light tube receptacle of the class described embodying: a basal sleeve section having an inwardly extending flange formed on its inner end; a cob in said sleeve section and having 35 a shoulder adapted to engage said flange; a cover section mounted on said sleeve over said cob; means mounted in said cover and engaging said cob for locking all of said sections in rigid engagement, said sleeve being provided with an in- 40 clined channel at its inner end; a sheath on
- said cover section extending over said channel in spaced relation therewith so as to form an inclined passage having an opening in the inner end of said receptacle; and a conductor plate mounted on said cob opposite said opening. 80
16. A light tube receptacle of the class described embodying: a basal section having a deep socket extending longitudinally therein and terminating in an end wall; an extending segment formed on said basal section and projecting beyond said end wall; a cover section engaging said extending segment and cooperating with said end wall and said segment to form a transverse chamber above said end wall; means for securing said cover section to said basal section; a conductor thimble in said basal section; and conductor means engaging said thimble and extending into said transverse chamber, the side wall of said receptacle being provided with an inclined passage opening into said transverse chamber above said end wall and having an outside opening in said side wall below said end wall. 85
17. A light tube receptacle of the class described embodying: a housing composed of insulating material; means at the lower end of said 100 housing for engaging a supporting plate, said housing being provided with a deep tapered socket extending longitudinally therein with its axis substantially normal to the base of said housing, and said housing being exteriorly provided with an offset taper so that one portion of its peripheral wall is of increasing thickness from the base of the housing to its upper end; a chamber in said housing; a conductor thimble in said housing below said chamber; conductor means engaging 105 said thimble and extending into said chamber; and an inclined channel formed in the portion of said wall which is of increasing thickness, said channel communicating with said chamber. 110
